GARMENT HANGER

Frederick H. Deknatel, La Grange, Ill., assignor
to Mackie-Lovejoy Manufacturing Co., Chicago,
Ill., a corporation of Illinois

Application January 25, 1939, Serial No. 252,821

2 Claims. (Cl. 223—96)

This invention relates to improvements in garment hangers of the type in which a pair of clamping members or jaws are hinged together and are moved to clamping position by a lever, as in my earlier Patent 1,955,792, issued April 24, 1934.

The object of the present invention is to provide an improved garment hanger of this type which is of sturdier construction and in which the closing lever for drawing the clamping jaws together and for releasing them, may be actuated a little more readily.

A contributory object is to provide a garment hanger in which the heavy wire hinge members are reinforced with sheet metal, one member having the clamping lever mounted thereon and the other member having a pulley mounted on the sheet metal reinforcement therefor.

A further object is to provide a garment hanger of the character just described, in which a light spring is provided to keep the clamping jaws apart somewhat when the hanger is not in use.

Additional objects and advantages will be apparent from the description of the commercial embodiment of the invention illustrated in the accompanying drawing, in which:

Fig. 1 is a perspective view of the garment hanger;

Fig. 2 is a section on a central vertical plane with the jaws open;

Fig. 3 is a section on the line 3, 3 of Fig. 2; and Fig. 4 is a section on the line 4, 4 of Fig. 2.

The jaws or clamping members, as shown, are made preferably of strips of wood 10 lined with felt pads 11 on their inner surfaces at the ends, the middle portions being preferably made thinner so that the clamping engagement is effected primarily by the ends of the clamping members. Said members may, of course, be made of other material, and are connected by a hinge formed from heavy wires or metal rods of small diameter, the axis of the hinge being shown at 12. There are two such rods 13 and 14, having their ends received in openings in the wooden clamping members, the rod 14 being bent around portions of the rod 13 in the form of helices, as shown at 15, permitting the parts to swivel about said axis 12.

The middle portion of what may be called the rear rod 14 is bent down into substantially U shaped form, as shown at 16 and this portion is reinforced by a sheet metal member 17 the sides of which are bent around to grip the parallel arms of the U member. The bottom of the reinforcing metal is notched out at 18 and the lock-

ing lever 19 is mounted at this point by bending its end around the supporting wire.

The front member of the hinge 13 is made in the form of two wires or small rods having their adjacent ends bent down parallel to each other but not directly connected. They are held in fixed, spaced relation, however, by another sheet metal reinforcing member 20, having its sides bent around the parallel lengths of wire as shown. This reinforcement is also notched out at the bottom at 21 and supports a small transverse shaft 22 on which the pulley 23 is mounted. This pulley, although a small one, is of substantial diameter as compared with the diameter of the locking lever 19 by which it is engaged. The sheet metal reinforcement forms a sturdy mounting for the pulley and resists bending of the wire during the clamping action and the rear reinforcement has a generally similar function. The end of the locking lever is formed as a hook as 20 in the earlier patent so that the device may be suspended from above when the jaws are clamped together.

When said jaws are unclamped they tend to spread apart a little due to the provision of a helical spring 24, the ends of which tend to press the jaw members in opposite directions, as will be apparent.

The clamping lever rides freely over the pulley as said lever is being swung to clamping position, providing an effective leverage and making it very easy to clamp the jaws together, even though, before clamping, they are held apart at a considerable angle. The pulley also reduces wear, prolonging the life of the device. The lever, it will be noted, is bent in such a way as to form a hook at the bottom, the curvature being such that said lever, after it has ridden over the roller almost to its final position, passes the dead center so as to resist the action of the spring in tending to press the jaws apart. In other words, the lower end of said lever serves to lock the parts together.

In referring to certain parts as in horizontal position, such terms are used merely in a relative sense and as a convenient means of description, as the operation is, of course, independent of the position of the parts, although the device usually hangs from a support above it, over which it is hooked.

I claim:

1. A garment hanger comprising two clamping members, hinged arms secured thereto, one of said arms being made of two lengths of rod having adjacent ends, a metal member to which each of

- said ends is secured, and a roller mounted on said member, the other of said arms being made of a rod also and having a metal part embracing an intermediate portion of said rod, and a locking device hinged to said other rod adjacent said metal part and arranged to engage said roller and draw said clamping members toward each other.
2. A garment hanger comprising two clamping members, hinged arms secured thereto, one of said arms being made of two lengths of rod having adjacent ends, a metal member to which each

of said ends is secured, and a roller mounted on said member, the other of said arms being made of a rod also and having a reinforcing sheet of metal bent around an intermediate portion of said rod, said sheet of metal being formed to expose a portion of said other rod, a hook-shaped locking device hinged to said other rod adjacent said sheet metal member and arranged to engage said roller and draw said clamping members together.

FREDERICK H. DEKNATEL.
